UNITED STATES PATENT OFFICE

173,268

BALLET SLIPPER

Lewis Kramer, Philadelphia, Pa.

Application November 6, 1953, Serial No. 27,483

Term of patent 7 years

(Cl. D7—7)

To all whom it may concern:

Be it known that I have invented a new, original, and ornamental Design for a Ballet Slipper, of which the following is a specification, reference being had to the accompanying drawing, forming a part hereof.

I claim:

The ornamental design for a ballet slipper, as shown.
